UNITED STATES PATENT OFFICE

157,637

INSULATED METALLIC CONTAINER

Herschel D. Shawver, Wichita, Kans., assignor to
The H. D. Shawver Company, Inc., Wichita,
Kans., a corporation of Kansas

Application March 3, 1948, Serial No. 144,884

Term of patent 3½ years

(Cl. D58—17)

To all whom it may concern:

Be it known that I, Herschel D. Shawver, a citizen of the United States, residing at Wichita, in the county of Sedgwick and State of Kansas, have invented a new, original, and ornamental Design for Insulated Metallic Containers, of which the following is a specification, reference being had to the accompanying drawing forming a part thereof.

In the drawings:

Fig. 1 is a perspective view of an insulated metallic container showing my new design; and
Fig. 2 is a plan view thereof.

I claim:

The ornamental design for an insulated metallic container, substantially as shown.

HERSCHEL D. SHAWVER.
